UNITED STATES PATENT OFFICE.

HENRY PIJSESENS, OF PHILADELPHIA, PENNSYLVANIA.

ARCH OR INSTEP SUPPORTER.

1,153,441.

Specification of Letters Patent. Patented Sept. 14, 1915.

Application filed June 10, 1915. Serial No. 33,228.

To all whom it may concern:

Be it known that I, HENRY PIJSESENS, a subject of the King of Belgium, residing at Philadelphia, in the county of Philadelphia 5 and State of Pennsylvania, have invented certain new and useful Improvements in Arch or Instep Supporters, of which the following is a specification.

The invention relates to arch or instep 10 supporting shoes, boots, slippers, etc., and the object of the invention is to incorporate within the shoe, or other footwear, a stiff arch or instep supporting member and to modify the construction of the shoe in a 15 manner that the said supporting member may be readily inserted in the shoe during manufacture of the latter to be firmly held against displacement and to afford no discomfort and give the most beneficial results 20 to the wearer.

With these and other objects in view, as will be brought out hereinafter, reference will be had to the accompanying drawings forming a part of this specification and 25 wherein like characters of reference designates corresponding parts throughout the several views, in which:

Figure 1 is a view in side elevation of a shoe equipped with the invention, parts being 30 broken away and shown in section, Fig. 2 is a view in horizontal section cut through line 2—2 of Fig. 1. Fig. 3 is a perspective view of the metal arch or instep supporting member. Fig. 4 is a bottom plan view of 35 the shoe in the process of manufacture, Fig. 5 is a vertical sectional view on line 5—5 of Fig. 1, and Fig. 6 is a view in vertical section taken on line 6—6 of Fig. 1.

Referring to the drawings, reference numeral 1 designates the insole, which conforms to the shape of the shoe. The leather upper 2 and cloth lining 3 conform with each other in shape and have their lower edges turned over the insole and other parts in 45 the usual manner preparatory to receiving the sole and heel. The counter stiffener consists of a single piece of thick and rather stiff leather fitted in the usual manner between the upper leather 2 and cloth lining 50 3 and preferably cemented to the said lining, said counter stiffener being designated by numeral 4. The said counter stiffener extends in the usual manner around the heel portion and partly along the sides of the 55 shoe, and one side portion of said counter stiffener is provided with an integral flap 5

which extends across the bottom of the shoe and has a tapered edge 6 which overlaps the correspondingly tapered edge 6' of the other side wall portion of the counter 4. At the 60 heel portion, the counter stiffener flap 5 does not extend entirely to the heel extremity of the shoe, but is cut away as at 5' thereby affording an opening in the counter member as a whole and likewise affording a cushion- 65 ing element for the shoe heel in the nature of an air space.

Between the counter stiffener flap 5 and the corresponding portion of the insole 1 is placed a metal or other stiff arch supporting 70 member 7, and between this member 7 and the insole is inserted a piece of felt or other padding 8, said padding being at least of sufficient area to cover and extend beyond 75 the outer edges of the metal arch or instep supporting member 7. The said metal supporting member 7 is extended laterally and upwardly into a wing portion 9 which fits the instep of the foot. The inner sole on one side of its shank portion is likewise extended into a wing portion 10, and this latter portion 10 not only serves to cover the wing portion 9 of the metal supporting member, but assists to a degree in supporting the arch or instep of the foot. The felt 80 8 prevents the metal supporting member 7 from being felt by the foot through the innersole. Tacks 11 passed through holes 12 provided in opposite ends of the metal supporting member 7 and clinched in the 85 innersole 1, secure said member 7 to said innersole.

The innersole with the metal supporting member 7 tacked thereto is prevented from shifting within the shoe by a line of stitching 14, which line is continuous around the entire peripheral edge portion of the innersole, with the exception of a break at one side portion of the shank of the insole. At the toe portion of the shoe, the stitching 14 passes through the welt 15, upper 2, lining 3, and partially through the innersole 1. At the heel portion of the shoe, these stitches 14 pass through the upper 2, counter stiffener 4, lining 3, innersole 1, and in some cases through the felt 8, according to the extension of the latter. Where the break occurs in the line of stitching 14, the innersole is not caught by the stitches, the stitching at that point, as in Fig. 6, being only through the welt 15, upper 2, counter stiffener side 4 and flap 5, and lining 3.

It is immaterial as to the type of stitching employed, the type adopted being the most suitable to the situation, and if necessary or desirable, the stitching may extend entirely through the insole instead of only catching into the under face thereof.

In the course of manufacture of the shoe, the felt 8 and metal arch supporting member 7 are inserted and the latter tacked before the stitching 14 is run, and when these parts are in place, the counter stiffener flap 5 is closed over said parts and its overlapping edges 6 and 6' then secured together by said stitching 14 and the stitching further employed as described to secure the insole to the other parts of the shoe.

What is claimed:

1. A shoe having an innersole, an outersole, and a counter stiffener, said counter stiffener including a flap passing across the bottom of the shoe between the innersole and outersole, and an instep supporter located between said counter stiffener flap and said innersole.
2. A shoe having an innersole, an outersole, and a counter stiffener, said counter stiffener including a flap passing across the bottom of the shoe between the innersole and outersole, an instep supporter located between said counter stiffener flap and said innersole, said counter stiffener and innersole being stitched together.
3. A shoe having an innersole, an outer-

sole, an upper, and a counter stiffener, said counter stiffener including a flap passing across the bottom of the shoe between the innersole and outersole, said upper, counter stiffener and innersole being stitched together.

4. A shoe having an innersole, an outersole, an upper, and a counter stiffener, said counter stiffener including a flap passing across the bottom of the shoe between the innersole and outersole, and an instep supporter located between said counter stiffener flap and said innersole, said upper, counter stiffener and innersole being stitched together.

5. A shoe having an innersole, an outersole, an upper, and a counter stiffener, said counter stiffener including a flap passing across the bottom of the shoe between the innersole and outersole, said upper, counter stiffener and innersole being stitched together there being a break in the stitching at the instep of the shoe, and an instep supporting member secured to the innersole between the latter and the counter stiffener flap and having a lateral extension extending through said break in the stitching.

In testimony whereof I affix my signature in presence of two witnesses.

HENRY PIJSESENS.
